BY George C. Heinrichs

ATTORNEY.

UNITED STATES PATENT OFFICE

FRANK SMETAK, OF ASTORIA, NEW YORK

TOY

Application filed April 8, 1930. Serial No. 442,521.

This invention relates to improvements in toys, particularly to a toy in which the rapid rotation of a slide bearing on its front and rear faces parts of letters, numerals, legends, representations of aeroplanes, automobiles, etc., which, when viewed in their state of rest will give no meaning, while during the rapid rotation of the slides the parts on front and rear will supplement themselves to form 5 arithmetical examples and their solutions, words, legends, representations of aeroplanes, automobiles etc., greatly to the amusement of children.

Another object of my invention is the provision of a toy which is comparatively simple and inexpensive yet durable and efficient in its operation.

A further object of my invention is the provision of a toy which comprises a trough 20 in which exchangeable slides are held for rotation with their end tenons in depressions of the end walls of the trough, and provided with supplementary inscriptions on front and rear faces, which in the state of rest have no 25 meaning but during the rapid rotation of the slides by means of air blown against the same through a tube will supplement themselves to form arithmetical examples, words, legends, or pictures.

A still further object of my invention is the provision of a toy equipped with rapidly rotating slides the slight noise made during the rotation of the slides to simulate the noise of aeroplane propellers, or running automobile engines, as the case may be much to the amusement of children, and the effect of which may greatly be augmented by suitable inscriptions such as for instance "What is it?"

These and other objects and advantages of my invention will become more fully known, as the description thereof proceeds, and will then be more specifically defined in the appended claims.

In the accompanying drawing, forming a material part of this disclosure:

Fig. 1 is a front elevation of a toy constructed according to my invention.

Fig. 2 is a longitudinal section through the 50 same.

Fig. 3 is a front elevation of the slide holder.

Fig. 4 shows a blank from which the slide holder is made.

Fig. 5 shows different embodiments of the 55 rotating slides.

Fig. 6 is a perspective view of the toy.

As illustrated, the toy comprises a slide holder 10 in shape of a trough having its end walls 11 and 12 equipped with median ears, having depressions 13 formed therewith. The blank from which the trough 10 is made has integrally formed therewith a projection 14 adapted to be rolled into a socket 15 the 60 inner end of which is cut away on top as at 16.

The socket or sleeve 15 is adapted to receive in its outer end a tube 17.

The slides to be used with my toy are each equipped at their ends with tenons 18, 70 19 adapted to fit into the depressions 13.

As examples of the many possible embodiments of slides, I have illustrated in Figure 5, a slide 20 provided at its front face with a lower colored portion 21, preferably colored black, while its upper portion 22 is white and carries one half of an arithmetical example or problem as for instance "3 times 8=24," while the rear face has an upper portion 23 preferably colored black or dark and a lower white portion 24 carrying the other half of the same arithmetical example inverted.

Another form of slide 25 has both of its faces, the front as well as the rear face colored dark or black and the front face is provided with the white letters "A E I A" spaced from each other, while its rear face carries the white letters "M R C" arranged so as to appear in the spaces between the letters 85 90 95

"A E I A" to supplement the same to the word "A M E R I C A", during the rotation of the slide.

The form of slide 26, also shown in Figure 5 has at its front face a lower black portion 27 and an upper white portion 28, the latter carrying the representation of one half, preferably the upper, of an aeroplane while its rear face has an upper black portion 29, and a lower white portion 30, the latter carrying the representation of the lower half of an aeroplane.

In operation, one of the slides 20, 25, or 26 is engaged with its end tenons 18, 19 into the depressions 13 in the end walls of the trough 10 and if now air is blown through the tubular mouth piece 17 against the slide the same will rapidly turn and on slide 20 the full solution of the example "3×8=24" will be visible greatly to the amusement and instruction of children, while the rapid rotation of slide 25 will result in making the word "A M E R I C A" visible. The rapid rotation of slide 26 will make the full aeroplane to become visible while the slight noise connected with the rotation will simulate the noise of the propellers etc.

It will be clear that any legend or representation may be placed on the front and rear sides of slides so as to supplement each other to form a perfect legend or picture during the rapid rotation of the slide as outlined above.

It will be understood that I have described and shown the preferred form of my toy and some of the slides which are used therewith, as examples of the many possible ways to practically construct my toy and slides, and that I may make such changes in the general arrangement and the construction of the minor details thereof as come within the scope of the appended claims without departure from the spirit of my invention and the principles involved.

Having thus described my invention, what I claim as new and desire to secure by Letters Patent is:

1. A toy comprising a trough shaped holder, slides rotatably held between the end walls of said holder and bearing on their front and rear faces marks conveying no meaning with the slides at rest, however, supplementing each other during the rotation of said slide to expose front and rear faces in rapid succession to the eye, to form intelligible results, and a tube combined with said trough allowing the blowing of air therethrough to impinge on said slides to rotate the same.

2. A toy comprising a trough shaped holder, ears on the end walls of said holder having depressions formed therein, a socket formed with said holder having its inner top end part cut away, and a tube adapted to be engaged in said socket, slides and end tenons on each slide adapted to fit into the

depressions of said end walls allowing a rotation of the slide by means of the air blown against the same through said tube, said slides bearing marks on their front and rear faces meaningless per se but supplementing each other during the rotation of the slide to form intelligible productions.

Signed at New York, in the county of New York, and State of New York, this 7th day of April, A. D 1930.

FRANK SMETAK.
